UNITED STATES PATENT OFFICE.

ROBERT M. LYNN, OF WILKINSBURG, PENNSYLVANIA.

RAIL-JOINT.

No. 836,517.

Specification of Letters Patent.

Patented Nov. 20, 1906.

Application filed September 18, 1906. Serial No. 334,493.

To all whom it may concern:

Be it known that I, ROBERT M. LYNN, a citizen of the United States of America, residing at Wilkinsburg, in the county of Allegheny and State of Pennsylvania, have invented certain new and useful Improvements in Rail-Joints, of which the following is a specification, reference being had therein to the accompanying drawings.

10 This invention relates to rail-joints; and its object is to provide a simple, effective, and durable joint without the employment of the usual bolts and nuts.

The construction of the improvement will 15 be fully described hereinafter in connection with the accompanying drawings, which form a part of this specification, and its novel features will be clearly defined in the appended claims.

20 In the drawings, Figure 1 is a view in perspective of the meeting ends of two railway-rails constructed in accordance with my invention, the rails being shown separated; and Fig. 2 is a transverse vertical section showing 25 the two rails joined.

The reference-numeral 1 designates the tread of one of the rails, the end of which is cut away, a portion of the web 2 at the end of the rail being also removed. The meeting rail 3 has the lower portion of the web 4 cut away for a distance equal to the length 30 of the projecting cut-away web 2 of the opposite rail.

The rail 3 is provided on either side with 35 integral oppositely-disposed splice-bars 5 and

6, the web portions 7 of which are adapted to fit under the tread of the adjacent rail, while the base portions 8 of said spliced bars overlap the base of the adjoining rail.

As shown in Fig. 2, the web 2 fits below 40 the web 4 of the rail 3, thus bringing the opposing end faces 9 of the two rails together.

The improvement constructed as above described affords an effective and durable joint and adapts the rails to be readily connected without the use of bolts and nuts and permits them also to be readily disconnected when necessary.

Having fully described my invention, what I claim, and desire to secure by Letters Patent, is—

1. The combination with a railway-rail having its web and tread cut away at one end, of a meeting rail having integral splice-bars overlapping the web and base of the 55 other rail and having its web cut away to receive the web of the adjacent rail.

2. In a rail-joint, the combination with a rail having its tread and a portion of its web cut away at one end, of a meeting rail having 60 its web cut away to receive the web of the other rail, and oppositely-disposed splice-bars formed integral with said meeting rail to overlap the web and base of the other rail.

In testimony whereof I affix my signature 65 in the presence of two witnesses.

ROBERT M. LYNN.
